UNITED STATES PATENT OFFICE.

CHARLES H. REID, OF DANBURY, CONNECTICUT.

HAT-POUNCING MACHINE.

SPECIFICATION forming part of Letters Patent No. 659,259, dated October 9, 1900.

Application filed October 26, 1899. Serial No. 734,845. (No model.)

To all whom it may concern:

Be it known that I, CHARLES H. REID, a citizen of the United States, and a resident of Danbury, in the county of Fairfield and State of Connecticut, have invented certain new and useful Improvements in Hat-Pounding Machines, of which the following is a specification.

My invention relates to certain new and useful improvements in machines for pounding hats, and has for one object to simplify the construction of this class of machines.

A further object of my invention is to greatly improve the quality of product secured from machines of this description, as will be more fully hereinafter explained.

Referring to the accompanying drawings, which form a part of this specification, Figure 1 is a side elevation of my improved machine; Fig. 2, a plan view thereof; Figs. 3 and 4, detail sectional elevations on the lines $x x$ and $y y$, respectively, on Fig. 2; and Fig. 5, a detail perspective view of a modified form of templet for use in connection with the manufacture of soft hats.

Similar letters of reference denote like parts in the several figures.

A is the bed of the machine, supported in any suitable manner, and B is a short vertical shaft journaled within a bearing b , supported on said bed-plate. To the upper extremity of the shaft B is secured a hat-block chuck C, upon which is placed in the usual manner a hat-block c, carrying the hat-body (not shown) to be pounced. Journaled in a bearing d on said bed-plate is a vertical shaft D, to the upper extremity of which is secured a templet E, which, as regards conformation, is a duplicate of the block c, over which the hat-body to be pounced is secured.

F E' are two sprocket-wheels of equal diameters secured, respectively, upon the vertical shafts B D, and G is a sprocket-chain which serves to gear said sprockets together, so that the shafts upon which the latter are respectively mounted will rotate in harmony with each other.

H is a pulley tight on the shaft B and driven by a belt I, running from the driving mechanism, which I will now describe.

J is a short horizontal shaft mounted in bearings K on the bed-plate, and L M N are

pulleys tight on a sleeve P, which loosely surrounds said shaft intermediate of said bearings K.

55

Q is a loose pulley adjacent to the pulley M, and R is a driving-belt running from a counter-shaft, (not shown,) as in ordinary shop practice, which belt by being shifted will run equally as well upon either of the 60 pulleys M Q.

The belt I, previously referred to, connects the pulley L with the pulley H, and when the driving-belt R is in engagement with the pulley M, as seen in Fig. 2, the hat-block c and 65 templet E will be rotated synchronously.

The pouncing or fur-grinding mechanism is carried by an arm pivoted in such manner as to be capable of swinging freely over the top and around the sides of the hat-body, so 70 that the grinding-surface may be properly applied thereto, and I will now describe such mechanism.

S is a yoke or frame pivoted around the shaft J, so as to swing freely within a vertical plane.

75 T is a short hollow shaft or spindle housed within a socket U, formed on the yoke S, and V is a rod which passes through a bearing V', formed on the upper extremity of said shaft 80 T and at right angles therewith. Said rod V is restrained from any lengthwise movement by the collars v, but is free to turn within its bearing after the manner of a swivel. W is the pouncing-arm, which is secured to said 85 rod by clips w. It will thus be seen that the arm W is capable of swinging in both horizontal and vertical planes and is at the same time free to turn on a longitudinal axis. In other words, the various joints of said arm W 90 form in effect a ball-and-socket connection.

X is a roller journaled on the pouncing-arm and carrying a tight pulley X', which is driven by a belt N', running from the pulley N.

95 Y is a slide which is preferably tubular in shape and telescoped over the arm W, which is likewise tubular, and Y' is a roller journaled on said slide.

Z is a sandpaper pouncing-belt adapted to run on the rollers X Y'.

100

e indicates elongated slots cut in the tubular arm W in the direction of the latter's length, through which a bolt f, carried by the slide Y, passes; and g is a coil-spring which bears

against said bolt, so that said slide and roller Y, carried thereby, will be resiliently thrust in a direction away from the roller X, whereby the pouncing-belt will be maintained sufficiently taut. An additional advantage of this construction is the facility with which the pouncing-belt may be put on or removed, the manner of so doing being too obvious to require further explanation.

10   h is a roller supported in position by pivoted links k, approximately midway between the rollers X Y and of somewhat greater diameter than the latter. The pouncing-belt incloses and travels around all three of said rollers, as clearly shown in Fig. 1, the roller h being located directly at that point where said belt comes in contact with the hat-body. The function of said roller h is to limit or shorten the arc of contact of the pouncing-belt with the hat-body, or, in other words, should the roller h be dispensed with the pouncing-belt would assume a slight concave form at the point where in contact with the hat-body, thus causing a greater area of both 15   said hat-body and belt to be in contact at the same time, a condition unsuited to the attainment of excellent results and materially affecting the quality of the product. Said roller h, though yieldingly supported, is not 20   25   in the nature of a soft, flexible, or elastic pad, since said roller is ordinarily made of wood and forms a substantial backing or reinforcement for the pouncing-belt, and I have been enabled to secure far superior results by the 30   35   employment of this construction than any heretofore used. The action of the pouncing-belt in connection with this roller h is such that the long coarse hairs are quickly removed from the hat-body, while but little 35   40   45   of the finer fur is cut away, thus enabling the manufacturer to use a hat-body of much lighter initial weight, thereby effecting a great saving in material and consequent reduction of the cost of manufacture.

45   l is a belt-shifter pivotally attached to the yoke or frame S, (as by being swung around the vertical pivot or shaft T,) and m indicates ears formed on said shifter, between which the free end of the horizontally-disposed rod V 50   55   projects. n indicates set-screws tapped within said ears m, whereby said shifter may be adjusted with respect to the end of the rod V in order to regulate the amount of lost motion or play between said rod and ears. l' is a wire loop or analogous device which surrounds the driving-belt R and is rigidly attached to said shifter, as by a screw-bolt l'', the function of said loop l' being merely to transmit the movements of said shifter to said belt.

60   65   The operation of the shifter l is effected by moving the rod V in a horizontal plane, as will be readily understood by reference to Figs. 1 and 2, and said shifter is provided with a brake-shoe t, adapted to engage the pulley N to stop the rotation of the latter when the driving-belt R is shifted from the tight pulley M to the loose pulley Q.

o is a rod or plunger the lower end of which bears upon the bed A, while the upper portion of said plunger is housed within the hole 70   75   low pivot T and is backed up by a coil-spring p, thereby forming a counterpoise for the pouncing-arm and parts connected therewith.

q is a rod or arm carrying at one end an anti-friction-roller r, while the opposite end of said rod is adjustably secured, as by set-screw s, within a bracket s', carried by the pouncing-arm W. The function of the arm and the templet E, upon which the former bears, (by the roller r,) is simply to guide 80   85   the pouncing-arm properly around the hat-body, whereby the action of the pouncing-belt thereon may be rendered uniform, thus overcoming any liability of cutting too deeply into said hat-body at the longer diameters thereof. It will also be understood that by the use of said adjustable arm q the depth to 90   95   which the pouncing-surface is required to cut may be properly adjusted, so that any degree of fineness of cut may be readily obtained.

The operation of my improved machine is as follows: When at rest, the pouncing-arm occupies the position shown in dotted lines in Fig. 2, with the driving-belt R running upon the loose pulley Q and brake-shoe t bearing against the side of the pulley N. After a hat-body has been properly secured over the block c the operator grasps the handle u and moves the pouncing-arm V in a horizontal plane toward the hat-body, but somewhat above the latter. This movement of said pouncing-arm will shift the driving-belt R from the loose pulley Q to the tight pulley M, thereby effecting the revolution of the hat-block and hat-body secured thereon and also the pouncing-belt and templet E. The pouncing-arm is then depressed until the guiding-arm q bears against the revolving templet E. Said pouncing-arm is then guided around said templet by the operator, beginning, preferably, at the tip of the hat-body and finishing at the brim portion, the operator taking care to keep said guiding-arm in contact with the templet, the experience and judgment of said operator being relied upon to determine the proper amount of pouncing that the hat-body should receive. As soon as the hat-body has been pounced sufficiently the operator thrusts the pouncing-arm in a horizontal plane away from said hat-body to 105   110   115   the position shown in dotted lines in Fig. 2, thereby shifting the driving-belt R from the tight pulley M to the loose pulley Q and causing the brake-shoe t to engage the pulley N and bring the parts to a standstill.

The pouncing-belt is of course run at a very high rate of speed; but the speed of the hat-block and templet is comparatively slow, so that no considerable difficulty will be encountered in keeping the pouncing-arm guided by 120   125   130   said templet.

The revolving templet and hat-block shown in the drawings are round in cross-section; but it will of course be understood that the

block and templet may be of any of the usual oval shapes.

Soft hats are usually pounced upon a block round in cross-section, and in instances where this sort of block is used it is not necessary to employ a rotatory templet, since a stationary skeleton templet E^2 of the proper conformation, such as is illustrated in Fig. 5, will answer the requirements of this particular class of work equally as well; but I greatly prefer the rotatory form of templet, for the reason that the machine may be more readily adapted to the various shapes of blocks.

Having thus described my invention, what I claim as new, and desire to secure by Letters Patent, is—

1. In a hat-pouncing machine, the combination of a pouncing-arm pivoted as described, pouncing mechanism carried by said arm, suitably-mounted driving mechanism, operative connections between said driving mechanism and pouncing mechanism, a rotatory hat-block, operative connections between said block and said driving mechanism, with automatically-operated instrumentalities intermediate of said pouncing-arm and driving mechanism, whereby said hat-block and pouncing mechanism will be set in motion when said pouncing-arm is moved in a direction toward said hat-block, and brought to a standstill when said arm is moved in the opposite direction, substantially as set forth.
2. In a hat-pouncing machine, the combination of a pouncing-arm pivoted as described, pouncing mechanism carried by said arm, suitably-mounted driving mechanism, operative connections between said driving mechanism and pouncing mechanism, a rotatory hat-block, operative connections between said hat-block and said driving mechanism, with automatically-operated instrumentalities intermediate of said pouncing-arm and driving mechanism, whereby the various rotatory members will be set in motion when said pouncing-arm is moved in a direction toward said hat-block, and brought to a standstill when said arm is moved in the opposite direction, and an adjustable guide-arm carried by said pouncing-arm adapted to bear upon a templet synchronously rotated with said hat-block, substantially as set forth.
3. In a hat-pouncing machine, the combination of a pouncing-arm pivoted as described, pouncing mechanism carried by said arm, suitably-mounted driving mechanism, oper-

ative connections between said driving mechanism and pouncing mechanism, a rotatory hat-block, operative connections between said block and said driving mechanism, with automatically-operated instrumentalities intermediate of said pouncing-arm and driving mechanism whereby said pouncing mechanism will be set in motion when said pouncing-arm is moved in a direction toward said hat-block, and brought to a standstill when said arm is moved in the opposite direction, substantially as set forth.

4. In a hat-pouncing machine, the combination of the bed or frame, pulleys which constitute the driving mechanism suitably journaled thereon, a yoke pivoted so as to swing in a vertical plane, the pouncing-arm swivelly connected to a rod which latter is pivoted to said yoke in such manner as to be capable of swinging in a horizontal plane, a belt-shifter and brake carried by said yoke and adapted to be engaged by said rod, pouncing mechanism carried by said pouncing-arm, operative connections between said pouncing mechanism and driving-pulleys, with a rotatory hat-block suitably journaled on said bed, and operative connections between said hat-block and driving-pulleys, substantially as described.

5. In a hat-pouncing machine, the bed or frame, pulleys which constitute the driving mechanism suitably journaled thereon, a yoke or frame pivoted so as to swing in a vertical plane, the pouncing-arm swivelly connected to a rod which latter is pivoted to said yoke in such manner as to be capable of swinging in a horizontal plane, a belt-shifter carried by said yoke and adapted to be engaged by said rod, pouncing mechanism carried by said pouncing-arm, operative connections between said pouncing mechanism and driving-pulleys, an adjustable guide-arm carried by said pouncing-arm and adapted to bear upon a suitably-shaped templet, in combination with a rotatory hat-block and operative connections between said hat-block and said driving-pulleys, substantially as described.

Signed at Danbury, in the county of Fairfield and State of Connecticut, this 21st day of October, A. D. 1899.

CHARLES H. REID.
